UNITED STATES PATENT OFFICE.

HAROLD M. MACCAUSLAND, OF WORCESTER, MASSACHUSETTS.

AUTOMOBILE-SIGNAL.

1,071,525.

Specification of Letters Patent. Patented Aug. 26, 1913.

Application filed March 8, 1912. Serial No. 682,497.

To all whom it may concern:

Be it known that I, HAROLD M. MACCAUSLAND, a citizen of the United States, residing at Worcester, in the county of Worcester and State of Massachusetts, have invented certain new and useful Improvements in Automobile-Signals of which the following is a specification.

This invention relates to signals adapted to be applied to automobiles and the like for signaling following vehicles as to the movements of the vehicle carrying the signal so that likelihood of accident will be reduced.

An object of the present invention is to provide a plurality of arms carrying each a signal such as "Stop," "Back," "Right" "Left" etc., each arm being electrically actuated and controlled by the driver of the vehicle, any particular signal being displayed instantly by simply closing a switch such as a push button or the like within convenient reach of the driver.

A second object of the invention is to provide means whereby a signal lamp will be lighted simultaneously with the displaying of any particular signal, the signal lamp corresponding to the signal being of a different color than its neighbor's such as a red lamp for the signal "Stop" a green lamp for the signal "Right" etc., each signal lamp circuit being mechanically closed by the corresponding arm as the latter moves to operative position.

A still further object of the invention is to provide a device of this character which will be compact in form and will be composed of a few number of simple parts which will not easily get out of order.

With the above objects in view the invention consists of certain novel details of construction and combination of parts herein-after fully described and claimed, it being understood that various modifications may be made in the minor details of construction within the scope of the appended claims.

In the accompanying drawings forming part of this specification:—Figure 1 is a front elevation of the device. Fig. 2 is a cross sectional view taken on the line 2—2 Fig. 1, with parts in elevation. Fig. 3 is a

cross sectional view taken on the line 3—3 Fig. 2 with parts broken away and with parts removed. Fig. 4 is a diagrammatic view showing the electrical wiring of the device.

Referring now to the drawings in which like characters of reference designate similar parts, 10 designates a substantially cylindrical casing having aligned sight openings 11 in the front wall and disposed on opposite sides of the center thereof. The arms are mounted within the casing and turn about a concentric axis, and in the present instance two arms 12 and 13 are illustrated, the shaft 14 of the arm 12 being mounted to turn in suitable bearings 15 secured to the front and rear wall of the casing, and the shaft 16 of the arm 13 being in the nature of a sleeve which surrounds the shaft 14. Any desired number of the arms may be used, and each arm is normally held in vertical position. Each arm is provided on its advanced face with a sign in two parts as shown, such as "Stop" "Back," "Right" "Left" or the like, the sign being displayed through the sight openings 11 upon the arm being rotated to a horizontal position.

For rotating the arms to operative position I provide solenoids 17 and 18, having movable cores 19 and 20 which are connected through the instrumentality of links 21 and 22 to cranks 23 and 24 carried by the shafts of the arms as clearly shown in Fig. 2. Upon either solenoid being energized the corresponding arm will be rocked into horizontal position and the sign carried thereby exposed by the sight openings. For returning the arms to released position after each actuation, helical springs 25 and 26 are connected to the cranks 23 and 24 of the arms and to the casing.

At night it is desirable to illuminate the signal displayed while at the same time to display a light having a distinguishing color which may be associated with a particular signal so that the color of the glowing lamp may be used to warn following vehicles when the signal itself displayed on the arm is not visible. To attain this end I mount incandescent lamps 27 and 28 on the casing,

a lamp for each arm, and each lamp being of a different color from its neighbor, and furthermore being of such a color as may readily be associated with the related sign, 5 such as a red lamp for the sign "Stop," a green lamp for the sign "Right" etc. Each lamp is mechanically thrown into circuit as the related arm is moved to operative position, and for attaining this end I provide 10 the following mechanism:

Arranged within the casing are brackets 29 and 30 preferably formed of insulating material, knife switches 31 and 32 being disposed upon the outer ends of the brackets 15 and arranged in such a manner that upon the descent of the cranks 23 and 24, the switches will be closed. This construction is shown most clearly in Fig. 3. The switches control independent circuits which 20 actuate the incandescent lamps, and it will be seen that when any particular arm is moved to operative position, the related switch will be closed and the related lamp actuated. Each lamp is of ordinary construction 25 and is equipped with the usual key switch in the socket as indicated at 33 in order that the lamps may be cut out during the daytime when not needed.

By now referring to Fig. 4 the electrical 30 wiring for the manual control of the device may be seen. Both solenoids have a pole connected to a common conductor wire 34 which is connected to one pole of a battery 35 or other source of electrical energy. Each 35 solenoid has the remaining pole connected to a related push button situated within convenient reach of the vehicle driver as for instance upon the steering wheel of the automobile or the like, the connecting wires 40 being designated at 36 and 37 and the push button at 38 and 39. Both push buttons are connected to a common conductor wire 40 which is connected to the battery as shown. In operation suppose that the driver presses 45 the push button 38. A circuit may be traced through the wire 40, push button 38, wire 36, solenoid 17, and wire 34 to the battery. When this circuit is closed the core 19 of the solenoid will be drawn into the solenoid 50 and the related arm 12 moved to operative position.

By again referring to Fig. 4 it will be seen that both incandescent lamps have a pole connected to a common conductor wire 55 41, the remaining poles of the lamps being connected by conductor wires 42 and 43 to the common conductor wire 34 of the solenoid. A conductor wire 44 is connected to the wire 41 and to the wire 40. As above 60 stated upon the actuation of each arm to operative position, the related switch will be closed; consequently upon the solenoid 17 being energized, the switch 31 will be closed, and a circuit may now be traced from the

battery through the wire 40, wire 44, wire 65 41, lamp 27, wire 42, and wire 34 to the battery, and when this circuit is closed the lamp 27 will glow unless, as above stated, the key switch of the lamp is opened.

What is claimed, is:—

1. A signal device including a casing having a sight opening on each side of the center of one face, a shaft in said casing, an oscillating signal arm having an integral sleeve surrounding said shaft and displaying 70 a sign in two parts, a crank arm on said sleeve, a tension device connected to said crank arm and to said casing and normally holding said arm concealed within said casing, and means connected to said crank arm 75 and serving to oscillate said arm against the tension of said device whereby to expose both parts of said sign through respective sight openings.

2. A signal device including a casing having a sight opening on each side of the center of one face, a shaft in said casing, a pair of oscillating signal arms on said shaft, a crank arm operatively connected to each signal arm, a tension device connected to 80 each crank arm and connected to said casing and normally holding both signal arms extending in parallelism and out of registration with said sight openings, each arm displaying 85 a sign in two parts, and means connected to said crank arms for selectively oscillating each arm through an arc of ninety 90 degrees to bring both parts of the sign displayed thereby into registration with both of said sight openings.

3. A signal device including a casing having a sight opening on each side of the center of one face, a shaft in said casing, an oscillating signal arm having an integral sleeve surrounding said shaft, a crank arm 100 on said sleeve, a spring connected to said crank arm and to said casing and holding said arm normally extending out of registration with said sight openings, said arm displaying a sign, and means for oscillating 105 said arm through a ninety degree arc to expose said sign through said sight openings including an electro-magnet device, a movable core within and operatable by said electro-magnet, a link connected to said crank 110 arm and to said core, and a source of electrical energy in circuit with said electro-magnet.

4. A signal device including a casing having a sight opening, a shaft in said casing, 115 an oscillating signal arm having an integral sleeve surrounding said shaft, and displaying a sign, a crank arm on said sleeve, a tension device connected to said crank arm and to said casing and normally holding 120 said arm out of registration with said sight opening, an electro-magnet having a movable core connected to said crank arm and 125

operating to rock said signal arm to expose
said sign through said sight opening, a signal lamp, a source of electrical energy, a main electric circuit operatively connecting
said electro-magnet and said source of electrical energy, a shunt circuit from said main circuit to said lamp and a switch in said shunt circuit normally open and adapted to

be closed by said crank arm upon said electro-magnet being energized. 10

In testimony whereof I affix my signature, in the presence of two witnesses.

HAROLD M. MACCAUSLAND.
